to arms and other like and similar stiff materials, namely, wire, plastic, or any other suitable material, and to be resilient, that is, capable of being bent and returning to its original shape.

REINFORCED TROUSER HANGER

Filed in Boston, Mass., November 7, 1947, Serial No. 784,588; application filed November 7, 1947, Serial No. 784,588.

UNITED STATES PATENT OFFICE

2,456,014

TROUSER HANGER

Ernest J. Neaves, Boston, Mass.

Application November 7, 1947, Serial No. 784,588

2 Claims. (Cl. 223—88)

1

My invention relates to a hanger for men's trousers and the like.

An important object of the invention is to provide a trouser hanger which will not form an unsightly transverse crease in the legs of the trousers, such as occurs when trousers are hung over a conventional wire coat hanger.

A further object of the invention is to provide a trouser hanger for attachment to and use with conventional wire coat hangers now in use.

A further object is to provide a wire trouser hanger which is extremely simple in design, and inexpensive to manufacture.

A still further object is to provide a trouser hanger which will be extremely useful in dry cleaning establishments, where it is desirable to hang both coat and trousers on the same hanger, yet keep the transverse crease out of the trousers.

Other objects and advantages of the invention will be apparent during the course of the following description.

In the accompanying drawings, forming a part of this application and in which like numerals are employed to designate like parts throughout the same,

Figure 1 is a side elevation of the trouser hanger embodying the invention, and showing the same in use for supporting a pair of trousers, the trouser hanger being applied to a conventional wire coat hanger, which with the trousers is shown in dotted lines;

Figure 2 is a plan view of the trouser hanger;

Figure 3 is a vertical section on line 3—3 of Figure 1, the trousers being shown in full lines; and

Figure 4 is an end elevation of the trouser hanger.

In the drawings, where for the purpose of illustration is shown a preferred embodiment of the invention, the numeral 6 designates one side of the trouser hanger which includes an opposite parallel side 7 spaced slightly laterally from the side 6. The trouser hanger is preferably formed of a single length of resilient wire having its ends twisted together, as at 8, on side 7. The sides 6 and 7 are joined at opposite ends by inverted U-shaped end loops 9, integral with the sides 6 and 7.

The sides 6 and 7 include inclined downwardly converging straight ends 10 and 11, bent at their lower ends to form vertical upstanding straight trouser cuff support arms 12 and 13. The arms 12 and 13 are bent inwardly and at right angles at their top ends to form short horizontal shoulders 14 and 15, disposed at substantially the same ele-

vation as the loops 9. Disposed inwardly of the shoulders 14 and 15, the sides 6 and 7 further include opposed resilient V-shaped members including inclined downwardly converging portions 16 and 17, joined at their upper ends to the shoulders 14, and connected at their lower ends. The lowermost ends of the V-shaped members is a substantial distance below the bottom ends of arms 12 and 13. The opposed sides 6 and 7 are resiliently connected through the loops 9, and may be spread apart laterally at their bottoms. Also, the V-shaped members comprising portions 16 and 17 are resilient, and by closing or narrowing the top of the V-shaped members, the arms 12 and 13 may be moved inwardly longitudinally, with respect to the trouser hanger.

The loops 9 and ends 10 and 11 are adapted to straddle the inclined converging shoulders 18 of any conventional wire coat hanger. Such a coat hanger has a bottom horizontal portion or bar 19, disposed between the sides 6 and 7, when the trouser hanger is applied to the coat hanger. The trouser hanger is thus freely detachably connected to the coat hanger.

25 In use, a pair of trousers T, including legs L showing cuffs C may be applied to the trouser hanger, and suspended therefrom without creasing or wrinkling the same. A coat, or the like, may be mounted upon the coat hanger at the same time the trousers are being supported.

30 To apply the trousers T, the sides 6 and 7 of the trouser hanger are spread apart at their bottoms, and the legs L of the trousers are inserted upwardly between the sides. The outer sides of 35 the cuffs C are slipped over the arms 12 and 13, and shoulders 14 and 15, as shown. To facilitate this, the V-shaped members including portions 16 and 17 may be flexed inwardly, thus moving the arms 12 and 13 inwardly. When the 40 V-shaped members are released, the arms 12 and 13 spring outwardly and engage the ends of the cuffs C, Figure 1, thus tensioning the cuffs longitudinally.

45 It is to be understood that the form of the invention, herewith shown and described is to be taken as a preferred example of the same, and that various changes in the shape, size and arrangement of parts may be resorted to, without departing from the spirit of the invention, or the scope of the subjoined claims.

Having thus described the invention, I claim:

50 1. A unitary trouser hanger formed of wire and including spaced opposed sides, each side including an intermediate generally V-shaped portion and arms carried by the ends of the V-shaped

portion, the arms having shoulders at their tops, the arms being adapted for insertion within a cuff of trousers, and inverted substantially U-shaped loops connecting the lower ends of the arms of one side with the lower ends of the arms of the companion side, the U-shaped loops being adapted to be mounted upon the shoulders of a coat hanger.

2. A trouser hanger including spaced opposed sides, each side including an intermediate generally V-shaped portion and arms carried by the ends of the V-shaped portion, the arms being adapted for insertion within a cuff of trousers, and inverted substantially U-shaped loops con-

necting the arms of one side with the arms of the companion side, the U-shaped loops being adapted to be mounted upon the shoulders of a coat hanger.
